UNITED STATES PATENT OFFICE.

CHARLES W. WESTON, OF PAMPA, TEXAS, ASSIGNOR OF ONE-FOURTH TO ZACH WILSON, OF HIDALGO COUNTY, TEXAS, AND ONE-HALF TO F. E. OSBORN, F. B. FREE-LAND, AND GORDON GRIFFIN, ALL OF McALLEN, TEXAS.

DESIGN FOR A WALL-PAPER BORDER.

Application filed June 3, 1927. Serial No. 22,307. Term of patent 3½ years.

To all whom it may concern:

Be it known that I, CHARLES W. WESTON, a citizen of the United States, residing at Pampa, in the county of Gray and State of Texas, have invented a new, original, and ornamental Design for a Wall-Paper Border, of which the following is a specification, reference being had to the accompanying drawing, forming a part thereof.

The figure is a front elevation of a wall paper border, showing my new design.

I claim:

The ornamental design for a wall paper border, as shown.

CHARLES W. WESTON.
